UNITED STATES PATENT OFFICE.

ALFRED L. LOOMIS, OF TUXEDO PARK, NEW YORK.

GUN MOUNT.

Application filed August 14, 1919. Serial No. 317,606.

(FILED UNDER THE ACT OF MARCH 3, 1883, 22 STAT. L., 625.)

To all whom it may concern:

Be it known that I, ALFRED L. LOOMIS, a citizen of the United States, and a resident of Tuxedo Park, Orange County, and State 5 of New York, have invented an Improvement in Gun Mounts, of which the following is a specification.

The invention described herein may be used by the Government, or any of its officers or employees in prosecution of work 10 for the Government, or by any other person in the United States, without payment of any royalty thereon.

My invention relates to improvements in 15 gun mounts, the improvements being particularly directed to a mount disposing the gun close to the surface of the ground, and generally known in military parlance as a "Snake in the grass" mount.

One object of my invention is the provision 20 of a gun mount of the type stated capable of use advantageously in connection with a standard 75 mm. gun and cradle, French model 1897, although not limited to such 25 use, and which will provide a light mount in which the recoil under all conditions is maintained in a direct line with the trail.

Another object of my invention is the provision 30 of a mount of the character stated in which the complete maneuvering of the gun, the elevating and depressing and the swinging or traversing, as well as the firing may be conducted, and be under the absolute control of a single attendant or operator.

Another object of my invention is the provision 35 of a mobile mount which may be manufactured of commercial wrought iron bars and standard angle iron to insure the production of an inexpensive mount of light 40 weight while possessing the necessary durability, and which will be of such small and compact dimensions as to permit the transportation of at least four of the complete guns and their mounts upon a five ton 45 tractor.

Another object of my invention is the provision 50 of a mobile mount of low down type, capable of ready transportation and placing in position for use; which by its arrangement of parts will be easily camouflaged or obscured from vision; which will be capable of easy maneuvering; and which generally in all important respects will prove thoroughly efficient and practical.

With the attainment in view of the objects stated, and such others as are inherent in an invention of this character, the improvements consist of a mobile gun mount of the character named, embodying novel features of construction and combination of 55 parts substantially as shown, described and particularly defined by the claims.

In order that the construction in detail and the manner of manipulating my mount may be fully understood, as well as its points 60 of merit and advantage be appreciated, I invite attention to the accompanying drawings in which:—

Fig. 1 is a top plan view of a complete gun 70 and its mount constructed in accordance with and embodying my invention, the mount being shown in full lines in one position and in dotted lines in a position lateral thereof, to illustrate the manner of swinging or traversing the gun.

Fig. 2 is a side elevation of the complete gun and mount shown in position for operation, the spade serving as the fulcrum or pivot upon which the complete mount is traversed and also forming the stop or abutment for the trial of the mount.

Fig. 3 is a front elevation of the complete gun mount.

Fig. 4 is a perspective of the traversing 85 worm and its operating lever as well as the float by which said worm is carried; and

Fig. 5 is a perspective of the means for elevating and depressing the mount and a portion of the trail.

Referring by numerals to the drawings in 90 which the same numerals of reference are employed to denote similar parts in all the views:—

The numeral 1 designates the gun, 2 the usual cradle, 3 the tractor wheels, and 4 95 a bearing adjacent the muzzle of the gun, forming one of the means to support the gun on the cradle in recoil which structure or parts, for the purpose of illustration, constitute a standard 75 mm. gun and cradle, 100 French model 1897, although it will be understood that my improvements may be adapted to any character of gun and mount where they would perform their functions in an efficient and practical manner.

For the purpose of the present invention I employ the pair of angle shaped members or plates 5, to which are secured the pair of

angle shaped extensions 6, which provide the trail which carries the spade 7, adapted when the gun is "in battery," or position for use, to fit in the trench 8, and thus provide 5 a pivot as well as an abutment, permitting a ready swinging or traversing of the trail and providing an anchoring means.

To the pair of side members 5 are secured the spaced guides 9, between which is 10 mounted the yoke shaped member 10 known in military parlance as a "float," which mounting permits the forward end of the trail to move vertically within the yoke. To the lower portion of the yoke is secured the 15 worm 11, mounted between a pair of angle shaped brackets 12, which are suitably connected to the lower end of the float, and in which are journaled the trunnions 13, formed at the ends of the worm 11, the function of 20 which worm, as will presently appear, is to effect the swinging or traversing movement of the yoke member and a similar movement of the gun and its mount.

For the purpose of operating the worm 25 one of its trunnions carries a ratchet wheel 15, adapted to be engaged by the pivoted double toothed pawl 16, carried by the manually controlled lever 17, the movement of 30 which in either direction causes the pivoted pawl to rotate the ratchet wheel and consequently the worm, to cause the float or yoke shaped member to move or swing in either lateral direction with reference to the spade, thus providing a convenient and easily operated means for traversing the gun.

For the purpose of elevating and depressing the gun, I provide a vertical screw 18, mounted in a threaded guiding sleeve 19, carried by the upper closed end of the yoke 40 shaped member 10, while its lower end passes through a block 20, and carries a hand operated lever 21, provided with a twin toothed pawl 22 to engage the ratchet wheel 23 mounted rigidly upon the lower end of said 45 adjusting screw and operated by movement of the hand lever 21, through the engagement of the pawl 22, to rotate the screw 18 in opposite directions, which action raises and lowers the U-shaped members 9 and with 50 them the gun and its cradle.

The side plates 5 are provided with notches 24 for the reception of the trunnions of the gun cradle which trunnions may be clamped in place in said notches, as shown 55 most clearly in Fig. 2.

From the foregoing description taken in connection with the drawings it will be noted that the spade provides an anchoring means for the trail; that the hand levers are 60 disposed in such relation that a single operator can instantly move the worm to swing or traverse the gun and mount over a wide area and to either side; that operator can also manipulate the other hand lever for the 65 purpose of raising and lowering the gun to

the proper elevation or depression; and that the elongated trail provides a means for effectively guiding the mount in such manner that the recoil of the gun is at all times directly in line with the trail.

The arrangement and location of the operating levers, the traverse worm and the elevating and depressing screw is such that the operator may manipulate with one hand the lever to effect the traversing, while with the other hand he may take care of the lever for elevating and depressing the gun. Under ordinary conditions the traverse worm will function upon the surface of the ground, but should the ground not provide a firm support, a block of wood could be placed under the worm to form a coacting member with said worm to insure the required lateral or traversing movement.

It will also be noted that my improvements may be applied to guns and mounts in general use at a comparatively small expense, or the gun and mounts may be equipped with my improvements at the time of manufacture, and that such improvements 90 provide a light, compact and durable construction, capable of easy handling and transportation, and from all points of view insure a highly desirable and practical gun mount of this character.

Having described my invention, what I claim as new and desire to secure by Letters Patent, is:—

1. In a gun mount, the combination of a trail having means thereon to support a gun, 100 a worm adapted to engage the ground for traversing said mount about the spade as a center, and a handle for turning said worm.

2. In a gun mount, the combination of a trail having means thereon to support a gun, 105 a yoke shaped member adapted to seat on the ground and be slidably engaged by said gun support, means engaging said support and yoke and adapted to elevate and depress the gun support, said mount adapted to be traversed about the spade as a center.

3. In a gun mount, the combination of a trail having means thereon to support a gun cradle, a yoke shaped member adapted to seat on the ground and be slidably engaged by said gun support, means engaging said support and yoke and adapted to elevate and depress the gun support, and means on said yoke to traverse the mount about the spade as a center.

4. In a gun mount, the combination of a trail having means thereon to support a gun, a yoke shaped member adapted to seat on the ground and be slidably engaged by said gun support, means to elevate and depress said support on said yoke, and means secured to the yoke and adapted to engage the ground to traverse the mount about the spade as a center.

5. In a gun mount, the combination of a

- trail having means thereon to support a gun cradle, a yoke shaped member adapted to seat on the ground and be slidably engaged by said cradle support, means to elevate and depress said support on said yoke, a worm secured to the yoke and adapted to engage the ground to traverse the mount about the spade as a center, and means to rotate said worm.
- 10 6. In a gun mount, the combination of a trail having means thereon to support a gun, a yoke shaped member having a worm mounted in brackets thereon, and adapted to seat on the ground, said yoke being slid-

ably engaged by said gun support, a screw 15 to vertically adjust the gun support on the yoke, and means to rotate the worm to traverse the mount about the spade as a center.

7. In a gun mount, the combination of a 20 trail having means thereon to support a gun, a yoke shaped member adapted to seat on the ground and support the gun support, two U-shaped members secured to the gun support and spaced apart to form a guide 25 to receive the arms of the yoke, and means to adjust the gun support along said arms.

ALFRED L. LOOMIS.
